UNITED STATES PATENT OFFICE

131,894

DESIGN FOR AN AIR COMPRESSOR

Junius W. Houston, Arthurdale, W. Va., assignor
of forty-nine per cent to Harry A. Houston,
Pittsburgh, Pa.

Application November 7, 1940, Serial No. 96,404

Term of patent 7 years

To all whom it may concern:

Be it known that I, Junius W. Houston, a citizen of the United States, residing at Arthurdale, in the county of Preston and State of West Virginia, have invented a new, original, and ornamental Design for an Air Compressor, of which the following is a specification, reference being had to the accompanying drawings, forming a part thereof.

In the drawings, Figure 1 is a side elevational

view of an air compressor showing my design, Figure 2 is a front elevational view thereof as looking at Figure 1 of the drawings, Figure 3 is an end elevational view taken from the left of Fig. 1, and Fig. 4 is a top plan view thereof.

I claim:

The ornamental design for an air compressor, substantially as shown.

JUNIUS W. HOUSTON.
